DESIGN FOR A SHOE

John E. Harriss, New York, N. Y.

Application October 29, 1935, Serial No. 59,258

Term of patent 3½ years

To all whom it may concern:

Be it known that I, John E. Harriss, a citizen of the United States of America, residing in Manhattan, city of New York, county of New York, and State of New York, have invented a new, original, and ornamental Design for a Shoe, of which the following is a specification, reference being had to the accompanying drawing, forming part thereof.

I claim:

The ornamental design for a shoe, substantially as shown.

JOHN E. HARRISS.
